STRONG & ROSS.

Platform Scales.

No. 14,119.

Patented Jan. 15, 1856.

UNITED STATES PATENT OFFICE.

FRANCIS M. STRONG AND THOMAS ROSS, OF VERGENNES, VERMONT.

PLATFORM-SCALE.

Specification of Letters Patent No. 14,119, dated January 15, 1856.

To all whom it may concern:

Be it known that we, FRANCIS M. STRONG and THOMAS Ross, of the city of Vergennes, in the county of Addison and State of Vermont, have invented an Improvement in Platform-Scales; and we do hereby declare that the following is a full and exact description of the construction and operation of the same, reference being had to the accompanying drawings, forming part of this specification, of which—

Figure I is a plan, (the planking of platform removed;) Fig. II, a side sectional elevation through the platform timber B, Fig. I; and Fig. III, a detached end sectional elevation through the bearing *h* Fig. II, like letters of reference referring to the same parts in all the figures.

We construct a suitable frame work A of any required dimensions for the purpose of supporting the platform, and its appurtenances. The platform is not shown in the drawing, but B, B, represent its main timbers placed horizontally, and parallel to each other within the frames A. Opposite to the ends of these beams, and attached firmly to the frame A, are L shaped supports *f*, their lower portions projecting inwardly and horizontally under the timbers B and sustaining upon the bearings *i* two shafts C, C, which rest thereon upon V shaped pivots (*c*), the edges of which are at or above the centers of the sections of the shafts. Upon pieces projecting inwardly from the shafts C, under each extremity of the timbers B, B, are other V shaped pivots *c*, each sustaining intermediate bearing pieces *h*, upon which the ends of the platform timbers B rest. To the extremities of the shafts C are secured two arms or levers D, at any desired angle horizontally, they are prolonged until they meet the steelyard rod with which they are connected and form together the angular levers C, D.

The above arrangement presents many advantages. By passing the levers under or through the extremities of the platform timbers the necessity of mortising or cutting away the said timbers in the centers of their length to allow the levers to pass to the side of the scale (where they connect with the beam) is entirely obviated, the full strength of the timbers is presented, and their liability to come in contact with the levers by springing or otherwise is prevent-

ed. Also by prolonging the arms D until they meet and connect directly with the steelyard rod, we not only save expense in construction but simplify the apparatus, and materially increase its reliability and efficiency.

The intermediate bearing pieces *h*, have upon their upper surfaces, concavities corresponding with others upon the proximate faces of the shoes *g*, which are on the under surfaces of the timbers B. In each pair of the concavities are placed balls or their equivalents which support the platform and admit of its horizontal vibration, or limited motion, in any direction when any disturbing force is applied, which may cause it to come in contact with the sides of the frame. When the force is removed the platform is restored to its proper position clear of the frame by its own gravity, the balls *e* causing the deepest portion of each concavity to coincide with that of its fellow.

The bearings *i*, which are in the supports *f*, are made self adjustable, to compensate for any irregularity in the positions of the V shaped pivots or in the bearings themselves. They have cylindrical shanks projecting at right angles into corresponding sockets where they are each secured by a screw passing through the support *f* into the axis of the shank in such a manner as to admit of motion on its axis only.

All the bearings *i* are constructed with projections near their centers taking into notches on the pivots the projections fit at their bases to the corresponding portions of the notches, but space is left above to avoid contact. The relative positions of the parts are thus prevented from changing longitudinally, the friction being by this improvement reduced to a minimum.

We are aware that flanges have been used to keep the pivots in position, but the friction caused by the contact of their surfaces with the ends of the pivots has not been duly considered, and much inaccuracy in the scales has been the result.

We do not claim operating the beam by means of bent levers connected with the steelyard rod, through an intermediate lever, but—

What we claim as our invention and desire to secure by Letters Patent is—

1. The use of corresponding concavities and balls in combination with the proximate

faces of the intermediate bearing pieces *h*, and the shoe *g* substantially as described and for the purposes specified.

2. The adjustable bearings *i*, in combination with the pivots *c*, substantially as described and for the purpose specified.

3. The combination of the projections on the bearings *i*, with the notches in the pivots *c*, constructed as described for the purposes specified.

CARLOS BLAKE.

To the Commissioner of Patents:

20 Your petitioners, FRANCIS M. STRONG and THOMAS Ross, of Vergennes, in the county of Addison and State of Vermont, represent that they are the inventors, patentees, and owners of certain Letters Patent for 25 Improvement in Platform Scales, granted to them on the 15th day of January, 1856, for which, under a special act of Congress, they are now applying for an extension; that they have reason to believe that

through inadvertence, accident, or mistake 30 the specification and claim of said Letters Patent are too broad, including that of which said patentees were not the first inventors. Your petitioners therefore hereby enter their disclaimer to that part of the 35 claim in said specification which is in the following words:

“2. The adjustable bearings *i*, in combination with pivots *c*, substantially as described, and for the purpose specified.

40 And they further disclaim so much, and all, of the subject matter of the 3d claim, which is as follows: “3. The combination of the projections on the bearings *i*, with the notches in the pivots *c*, constructed as described for the purpose specified,” as would make said claim broader than the exact construction shown and described—that is, with the projection across the face of the bearings *i*, and the notches, in the pivots *c* without 45 any end or other projections on said pivots, as are found in the English patent of William Clark of 30th Dec., 1846, No. 11277.
